UNITED STATES PATENT OFFICE.

VENABLE J. GUTHRIE, OF CAMBRIA, VIRGINIA.

AIR COMPRESSOR OR PUMP.

1,108,434.

Specification of Letters Patent. Patented Aug. 25, 1914.

Application filed May 16, 1913. Serial No. 768,109.

To all whom it may concern:

Be it known that I, VENABLE J. GUTHRIE, a citizen of the United States, residing at Cambria, in the county of Montgomery and 5 State of Virginia, have invented a new and useful Air Compressor or Pump, of which the following is a specification.

The present invention appertains to air compressors or pumps, and aims to provide 10 a novel and improved air compressor or pump operating to displace the fluid under high pressure.

Another object of the present invention is to provide a compressor or pump which 15 shall dispense with the use of the ordinary cylinder and piston, so as to eradicate the objections existing in pumps of the cylinder and piston type.

A further object of the present invention 20 is to provide a compressor or pump operating under the displacement principle, which shall be comparatively simple, durable, and inexpensive in construction, as well as serviceable and efficient in its use.

25 With the foregoing general objects outlined and with other objects in view, which will be apparent as the nature of the invention is better understood, the present invention resides in the combination and arrangement of parts and in the details of 30 construction hereinafter described and claimed, it being understood that changes in the precise embodiment of the invention can be made within the scope of what is 35 claimed without departing from the spirit of the invention.

The invention has been illustrated in its preferred embodiments in the accompanying drawing, wherein:—

40 Figure 1 is a side elevation of the device. Fig. 2 is a plan view thereof, a portion being shown in section, the section being taken on the line 2--2 of Fig. 1. Fig. 3 is a sectional view taken on the line 3—3 of 45 Fig. 2. Fig. 4 is a transverse section taken on the line 4—4 of Fig. 1. Fig. 5 is a side elevation, partly in section, illustrating a modification or variation.

Referring specifically to the drawings, the 50 compressor or pump is preferably supported on a suitable base or bed 1, and embodies a main chamber or compartment 2 supported on the base 1. The chamber 2 is 55 preferably cylindrical and has the ends or heads 3 and 3' bolted or otherwise attached

thereto. The respective heads 3 and 3' of the chamber are provided with the outstanding conical pockets 4 and 4' arranged vertically thereof the axes 5 of the pockets 4 60 aligning with the axis of the chamber 2.

Disposed for reciprocation within the chamber 2, is a plunger 5 of suitable diameter, the same having pointed or conical ends 6 adapted to snugly enter the respective pockets 4 and 4', the plunger 5 being somewhat shorter than the chamber 2 so that the 65 length of stroke will be equal to the difference in lengths of the chamber and plunger.

The chamber 2 is preferably mounted on the rear end of the base 1, and the apex of the forward end of the plunger 5 is provided with a stem or plunger rod 7 passing through the apex of the pocket 4, while the apex of the rear end is provided with a tail or supplemental stem 7' passing through the 70 apex of the pocket 4'. Each of the pockets is provided with a stuffing box 8 at its apex, a gland 9 being secured within each stuffing box 8 to compress the packing disposed in the stuffing box against the respective stem 75 or tail, thereby effecting a tight fit.

A guide 10 is mounted on the base directly in advance or in front of the chamber 2, and a cross head 11 is slidably carried by the guide 10, the free end, or rather 85 outer end, of the stem 7 being attached to the cross head, and a pitman or connecting rod 12 connects the cross head 11 with a crank disk 13 mounted on a shaft 14 supported by a pair of pedestals or pillow 90 blocks 15 carried by the base adjoining its forward end. The shaft 14 may be driven in any suitable manner, such as by means of a pulley wheel 16 keyed upon the shaft 14 between the pedestals 15, although it is 95 to be understood that other means may be employed, and that the rotary motion of the shaft 14 may be converted into the rectilinear or reciprocatory motion of the plunger in any well known manner.

Each of the pockets 4 and 4' is provided with a lateral port or inlet 17, the same being normally closed by a spring pressed valve 18, which seats outwardly against the inner end of the respective port, so that the 105 valves may open inwardly to admit the fluid, as will hereinafter appear.

A sleeve 19 embraces the plunger 5 and is of a length approximately equal to the plunger, omitting the conical ends of 110

the plunger. In other words, the stroke of the sleeve 19 is similar to the stroke of the plunger 5, the ends of the sleeve 19 being beveled, as at 20, to snugly engage within or 5 abut against the beveled annular gaskets 21 secured to the inner face of the heads 3 and 3'. The gaskets 21 are secured to the inner faces of the respective heads around the pockets or sockets 4 and 4', and are preferably 10 constructed of rubber, or other compressible material. The plunger 5 works snugly with the sleeve 19, and is preferably provided intermediate its ends with the packing rings 5^a for providing a tight fit 15 between the plunger and sleeve.

The chamber 2 is preferably provided with an extension or supplemental chamber or compartment 22 upstanding therefrom, especially when the device is employed as 20 a compressor, the outlet pipe 23 being preferably connected to the supplemental chamber or chest 22, although the outlet pipe may be tapped into the supplemental or main chamber at any suitable point.

25 The sleeve 19 is operated from the driving shaft 14, a novel gear or actuating mechanism being provided for this purpose. To this end, a rocking shaft 24 is journaled through the supplemental or auxiliary chamber 22, 30 and has a pair of depending arms 25 attached thereto and projecting within the main chamber 2 at the sides of the sleeve 19. The sides of the sleeve 19 are provided with the upright face plates 26 intermediate the 35 ends of the sleeve, wrist pins 27 projecting from the face plates 26, and the lower or free ends of the arms 25 being bifurcated or forked so as to engage over the respective pins 27. The oscillation of the shaft 24 is 40 thus adapted to impart a reciprocatory movement to the sleeve 19, so that the sleeve will slide upon the plunger.

To the outer end of the rocking shaft 24 there is secured a slotted lever 29 carrying 45 the adjustable slide 30, a block 31 being pivotally carried by the slide 30. A bolt 32 passes through the slot of the lever 29 and engages the slide 30 to clamp the slide in any adjusted position, while the block 31 50 carries a set screw 33.

A lever 34 is fulcrumed upon an upright or standard 35 carried by the base, the respective ends or arms of the lever 34 extending to the driving shaft 14 and chambers 2, 55 respectively. A cam 36 is keyed upon the driving shaft 14, the respective arm of the lever 34 having a fork 37 straddling the cam 36, rollers 38 being carried by the branches of the fork to engage the opposite 60 or upper and lower portions of the cam 36. The cam 36 is so designed that when the driving shaft 14 is rotated, the rear end or arm of the lever 34 will be intermittently raised and lowered at the respective ends of 65 the strokes of the plunger 5. The lever 34

may be spring pressed by means of a suitable spring 39, although this is not necessary.

A link 40 connects the rear arm of the lever 34 with the lever 29, the link 40 having its upper end reduced, as at 41, and passing through the block 31, the set screw 33 serving to bind the reduced portion 41 in any adjusted position with respect to the slide 30. Adjoining its lower end, the link 40 is provided with a longitudinal slot 42 in which a slide 43 is movable, coiled wire compression springs being disposed between the slide 43 and the ends of the slot 42. The springs 44 permit the slides 43 to yield in 80 either direction, for the purpose which will hereinafter appear.

In operation, as the shaft 14 is rotated, the plunger 5 will reciprocate within the chamber 2, the conical ends of the plunger snugly entering the respective pockets 4 and 4' at the ends of the strokes of the plunger. The timing of the sleeve actuating mechanism or gear is such, that when the plunger 5 is at one end of its stroke, the sleeve will be moved from the other end of the chamber 2 to the corresponding end of the chamber to which the plunger has moved, the sleeve being held against the respective end of the chamber while the plunger is moved toward the other end. The sleeve will thus be at rest against one end of the chamber 2, while the plunger is moving toward the other end, and as the plunger reaches and commences to leave the respective end of the chamber 2, the sleeve 19 will be moved quickly toward the said end of the chamber by the mechanism above described. The plunger has a continuous reciprocatory movement whereas the sleeve has an intermittent reciprocatory movement, the motion of the sleeve being quicker than that of the plunger, so that the sleeve may be moved from one end of the chamber 2 to the other end, while the pitman or connecting rod 12 passes dead center, or while the respective end of the plunger 5 enters and commences to leave the respective pocket. It will thus be manifest that when the sleeve 19 is seated against one end of the chamber 2, the respective beveled end 20 of the sleeve fits tightly within the respective gasket 21. The stroke of the plunger toward the other end of the chamber will cause the fluid within the chamber to become compressed, the plunger displacing the fluid as it moves toward the respective end of the chamber. Inasmuch as the sleeve fits tightly against the respective end of the chamber 2, and inasmuch as the plunger has a tight fit with the sleeve, air or other fluid will be drawn through the respective inlet port 17, and after the plunger has reached the end of the stroke, and the sleeve has left the respective gasket, the respective valve will close, and the air will thus co-mingle with the com-

pressed air or fluid within the chamber 2. Thus, during each stroke of the plunger, the air or fluid will be displaced by the respective conical or pointed end of the plunger, fresh air or fluid being drawn in through the respective ports. The slide 30 is so adjusted that the motion of the lever 34 will be slightly excessive, that is, the motion of the lever 34 will be slightly greater in proportion than the stroke of the sleeve 19, and as a consequence, when the sleeve is moved against one end of the chamber 2, the respective spring 44 will be brought under a greater compression, so as to tightly but yieldingly hold the sleeve against the respective end of the chamber 2 in order to provide a tight joint. To promote this function, the cam 36, has been stepped as at 36^a, so that as the cam rotates, counter clockwise, as seen in Fig. 1, the sleeve 19 will be rapidly moved toward the respective end of the chamber 2, and then will be given an additional strain, due to the stepped portion 36^a, so that the respective spring 44 may be brought under sufficient tension to tightly hold the end of the sleeve against the respective gasket 21. When the device is employed as an air compressor, the inlet ports 17 will communicate directly with the atmosphere and as the plunger and sleeve are reciprocated, the air within the chamber 2 will be compressed by displacement, and in this manner, the air or fluid may be compressed under high pressure with but a minimum expenditure of power, it being observed that the conical ends of the plunger reduces friction and permits of the displacement of air without great effort. When the apparatus is employed as a pump, the inlet ports 17 are connected to any suitable source of water, or other fluid, in order that when the sleeve 19 is seated against one end of the chamber 2, the stroke of the plunger toward the other end, will draw or suck the water or other fluid into the space created within the respective pocket and the sleeve, the water or fluid co-mingling with the fluid within the chamber 2 as the sleeve leaves the respective end of the chamber 2, and the operation being repeated during each stroke of the plunger and sleeve. The employment of the device as a pump is also as efficient as when the device is employed as an air compressor, the conical ends of the plunger reducing friction, and the fluid within the chamber 2 being displaced as the respective ends of the plunger are projected from the sleeve toward the respective end of the chamber.

From the foregoing, taken in connection with the drawing, the advantages and capabilities of the present device will be apparent to those versed in the art, and need not be described at length, it being noted that the objects aimed at have been carried

out satisfactorily, and that the present apparatus is an efficient and desirable one.

The present apparatus is susceptible to alterations, one modification being illustrated in Fig. 5. In the construction illustrated in Fig. 5, it will be observed that the supplemental or auxiliary chamber 22 is omitted, and that the sleeve 19 is provided with an upstanding lug or ear 27^a, a sleeve actuating stem or rod 25^a being passed slidably through the forward end or head of the chamber 2^a and being yieldingly connected to a horizontal reciprocatory member 34^a carried by an upright or standard 35^a supported on the base 1. The reciprocatory member 34^a has a depending fork or yoke 37^a, the branches of which straddle the cam 36^a secured to the shaft 14, rollers 38^a being carried by the free ends of the branches to contact with the cam. The stem 25^a carries a collar 43^a, coiled wire compression springs 44^a being mounted on the stem or rod 25^a and seating between the collar 43^a and the reciprocatory member 34^a so that the stem or rod 25^a will be yieldably actuated by the member 34^a as the cam rotates. The forward end or head 3^a of the chamber 2^a is preferably provided with the stuffing box 45 surrounding the stem or rod 25^a, a gland 46 being engaged into the stuffing box for compressing the packing therein against the stem 25^a to provide a tight fit.

The operation of the modification depicted in Fig. 5 is similar to that of the form above described, the construction, however, being somewhat simplified. Any form of sleeve actuating mechanism or gear may be employed with equal propriety, the form illustrated in Figs. 1 to 4, inclusive, however, being preferable, inasmuch as it permits of certain adjustments, in order that the sleeve may be held at a greater or less tension against the respective gaskets 21 under the various conditions under which the machine may be operated.

Summing up the cardinal or salient features of the present invention, it will be observed that the present apparatus is a comparatively simple, durable and inexpensive one; that there is eliminated the use of the ordinary cylinder and piston; that the fluid within the main chamber is compressed or otherwise discharged by the displacement caused by the reciprocation of the plunger and sleeve, which minimizes the expenditure of power, and increases the efficiency of the device; and that the present apparatus is improved generally in its construction and utility.

Particular attention is directed to the fact that the plunger and sleeve are of approximately equal length, and are each of a length over one-half the length of the chamber 2. This is of considerable moment, particularly in connection with the terminal 139

stems of the plunger slidably engaging through the ends of the chamber, in order that the plunger will be effectively supported for reciprocatory movements, and in order that the sleeve will be efficiently mounted for sliding movements upon the plunger. Thus, the ends of the plunger will be projected from the ends of the sleeve, so as to displace the fluid within the chamber, which is highly desirable.

Although the gaskets 21 may be constructed of rubber, they are preferably made of brass or suitable metal ground or machined to fit the beveled ends of the sleeve, so as to withstand the wear and other conditions to which they are subjected. The cam should also be of such design that the rollers continually engage the periphery thereof so as to prevent any lost motion or looseness of the sleeve actuating mechanism.

Having thus described the invention, what is claimed as new is:—

1. The combination in a device of the character described, of a chamber, a plunger disposed therein and having terminal stems slidable through the ends of the chamber, a sleeve slidable on the plunger and terminally abutable against the ends of the chamber, the plunger and sleeve being of approximately equal length and each being of a length over one half the length of the chamber, means connected to one plunger stem for reciprocating the plunger, and means for reciprocating the sleeve from one end of the chamber to the other when the plunger is at the ends of its strokes, the ends of the chamber having valved inlet ports to communicate with the ends of the sleeve.

2. The combination in a device of the character described, of a chamber, a plunger disposed therein having conical ends and stems projecting from the apices of the said ends, the stems being slidable through the ends of the chamber, a sleeve slidable on the plunger and terminally abutable against the ends of the chamber, the plunger

and sleeve being of approximately equal length and each being of a length over one half the length of the chamber, means connected to one plunger stem for reciprocating the plunger, and means for reciprocating the sleeve from one end of the chamber to the other, when the plunger is at the ends of its strokes, the ends of the chamber having conical pockets to receive the conical ends of the plunger, and the said pockets having valved inlet ports.

3. The combination in a device of the character described, of a chamber, a plunger reciprocable between the ends thereof, a sleeve slidable on the plunger and terminally abutable against the ends of the chamber, the ends of the chamber having valved ports to communicate with the ends of the sleeve, a shaft journaled for oscillation through the chamber, an arm attached to the said shaft within the chamber and having its free end operatively connected to the sleeve, and means connected to the outer end of the said shaft for intermittently oscillating it.

4. The combination in a device of the character described, of a chamber, a plunger reciprocable between the ends thereof, a sleeve slidable on the plunger and terminally abutable against the ends of the chamber, the ends of the chamber having valved ports to communicate with the ends of the sleeve, a shaft journaled for oscillation through the chamber, an arm attached to the said shaft within the chamber and having its free end operatively connected to the sleeve, an arm attached to the outer end of the said shaft, and actuating means adjustably connected to the last mentioned arm, and including yieldable means.

In testimony that I claim the foregoing as my own, I have hereto affixed my signature in the presence of two witnesses.

VENABLE J. GUTHRIE.
